US00D974565S

(12) **United States Design Patent** (10) **Patent No.:** **US D974,565 S**
Li (45) **Date of Patent:** **** Jan. 3, 2023**

(54) **PULSE OXIMETER**

(71) Applicant: **Guangdong Health Tree Medical Technology Co., Ltd.**, Guangdong (CN)

(72) Inventor: **Dong Li**, Guangdong (CN)

(**) Term: **15 Years**

(21) Appl. No.: **29/824,514**

(22) Filed: **Jan. 25, 2022**

(51) **LOC (14) Cl.** **24-02**

(52) **U.S. Cl.**

USPC **D24/169**; D24/167

Assistant Examiner — Kelly L Gross

(74) *Attorney, Agent, or Firm* — Che-Yang Chen; Law Office of Michael Chen

(57) CLAIM

The ornamental design for a pulse oximeter, as shown and described.

DESCRIPTION

FIG. 1 is a perspective view of the pulse oximeter showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings show portions of the pulse oximeter that form no part of the claimed design.

1 Claim, 8 Drawing Sheets
